INVENTOR.
E. D. Griffith.

BY

A. Hanulsky Jr.

ATTORNEY.

UNITED STATES PATENT OFFICE.

EDWARD D. GRIFFITH, OF TUCSON, ARIZONA.

RAILROAD LANTERN.

Application filed July 23, 1920. Serial No. 398,381.

To all whom it may concern:

Be it known that I, EDWARD D. GRIFFITH, a citizen of the United States, residing at Tucson, in the county of Pima and State of Arizona, have invented certain new and useful Improvements in Railroad Lanterns; and I do hereby declare the following to be a full, clear, and exact description of the invention, such as will enable others skilled in the art to which it appertains to make and use the same.

This invention relates to new and useful improvements in lanterns especially adapted for use on railroads to give signals and for various other purposes and has for its primary object the provision of a device of the above stated character which will be evenly balanced owing to its compactness and arrangement of parts, so that the same may be conveniently handled when giving signals or otherwise used.

Another object of this invention is the provision of a novel ventilating means which will insure proper burning of the flame and obviate any danger of the flame being extinguished by wind or storms or from rough use to which the device may be subjected.

A further object of this invention is the provision of means which will firmly lock the fuel bowl or receptacle to the frame and prevent accidental detachment of the same during the use of the device or in case the device is positioned on or struck by an object.

A still further object of this invention is the provision of a railroad lantern of the above stated character, which will be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which:—

Figure 1 is a front elevation, illustrating

a lantern constructed in accordance with my invention,

Figure 2 is a perspective view illustrating the frame, 55

Figure 3 is a vertical sectional view illustrating the device,

Figure 4 is a fragmentary sectional view illustrating the securing of the fuel bowl to the frame, 60

Figure 5 is a fragmentary sectional view taken on an enlarged scale illustrating the mounting of the ventilator in the hood,

Figure 6 is a bottom plan view, illustrating the hood, 65

Figure 7 is a detail view illustrating the ventilator,

Figure 8 is a detail sectional view illustrating the same.

Referring in detail to the drawings, the numeral 1 indicates a frame which includes vertical members 2 and annular members 3 and which members are constructed from a heavy gage wire and are secured together in any desired manner. The upper annular member 3 is bent upon itself to form loop members or ears 4 which are adapted to extend through eyes 5 formed on a pair of the vertical members 2. The eyes 5 are formed by bending the upper ends of said vertical members upon themselves and said loop members or ears 4 are adapted to receive the ends of a bail or handle 6. The lower annular member 3 is adapted to form a base or support for the frame and the side members between the lower and intermediate annular members are bent inwardly and outwardly to form attaching portions 7 which are soldered or otherwise secured to an annular chimney or globe supporting element 8. The lower portion of the globe or chimney supporting element 8 is curved inwardly as illustrated at 9 and is provided with an opening 10 to receive a fuel bowl or receptacle 11 and said opening 10 is disposed in a plane above the supporting annular member 3. An annular bead 12 is formed on the inner face of the globe supporting element 8 adjacent its upper edge and is adapted to form a seat for a globe or chimney 13, of any well known construction. The lower end of the chimney or globe extends

downwardly within the globe supporting element 8 below the bead 12 and is spaced away from the wall of said supporting element 8 so that the ventilating openings 14 formed 5 in the walls of the globe supporting element 8 will be unobstructed. The air is adapted to pass through the openings 14 and strike against the chimney or globe 13 and be deflected downwardly and inwardly 10 when it passes upwardly in the chimney or bowl around the burner 15 carried by the fuel bowl or receptacle 11 and which is located within the chimney or globe.

The curvature 9 of the globe supporting 15 element 8 also aids in deflecting the air under the lower edge of the chimney and upwardly therein about the burner so as to insure a proper burning of the flame on the wick of the burner and obviate a direct draft 20 against the flame.

The fuel bowl or receptacle 11 consists of a body 16 adapted to contain the fuel and has formed in its top wall 17 a screw threaded opening 18 to receive the burner 25 15 and its wick. A screen 19 is located within the body 16 and is provided with an opening 20 to permit the wick of the burner to extend downwardly in the body. The body 16 has formed thereon an annular and downwardly depending wall 21 of a diameter 30 greater than the diameter of the body 16 which has formed upon its lower edge an annular flange 22 adapted to engage the globe supporting element 8 about its opening 10 and against the outer face thereof. A pair of brackets 23 are secured to the outer face of the bottom of the body 16 within the supporting wall 21 and slidably supports substantially U-shaped locking 40 elements 24. The arms 25 of the locking elements 24 have interposed between the same an expansion spring 26 for the purpose of urging the locking elements away from each other. The arms 27 of the locking elements 45 have formed thereon right angled latch elements 28 that extend through slots in the wall 21 and engage the globe supporting element 8 upon its inner face and above the opening 10 to cooperate with the flange 22 in securing the fuel bowl or receptacle 11 within the chimney supporting element and provides a construction which will permit the easy removal of the fuel bowl or receptacle when desiring to clean the 55 burner or fill the body 16 with fuel. It is also to be noted that the locking elements 24 are confined within the wall 21 and are prevented from coming in contact with obstacles which may have a tendency to accidentally unfasten the bowl 11 from the chimney supporting element 8. Further, it is noted that the body 16 containing the fuel is supported a considerable distance away from the ground when the frame is

positioned on the ground thereby keeping 65 the fuel from coming in contact with the ground which has considerable advantage in extremely cold countries as fuel sometimes contains a large percentage of water or other freezing fluid and when allowed to contact 70 with snow or ice or frozen ground the same is liable to become frozen rendering the lamp void of further use until thawed out.

A hood 29 is hinged to the upper annular member 3 of the frame 1 and is detachably 75 secured to the frame at an oppositely disposed point by a spring catch 30 which consists of a resilient wire 31 secured to the hood upon the inner face thereof and has an annular related catch formed on its ends 80 which moves through a bracket 33 and engages the annular member 3 of the frame to retain the hood in engagement with the frame but which will permit the hood to be swung laterally of the frame when desiring 85 to remove the chimney 13.

The hood 29 is provided with a conical portion 35 which engages the upper annular member 3 of the frame 1 and a ventilating cap 36 provided with a series of openings 37 in its side wall. The cap 36 is of hollow formation and the top wall thereof has secured thereto a pair of resilient fastening members 38 adapted to pass through a slot 39 in a ventilating cap 40 and then bent 95 laterally to retain the plate 40 within the cap 36.

The ventilating plate 40 is located in the lower end of the cap 36 and is urged downwardly by means of an expansion spring 41 100 located between said plate and the top wall of the cap. The plate 40 has spaced ventilating slots 42' which permits the air passing upwardly through the chimney to escape through the cap 36 by way of the openings 37 thereof. Deflecting plates 43 are formed on the plate 42 and are disposed in diverging planes and overlie the slots 42'. Inclined and arcuately curved deflecting elements 44 are formed on the plate 40 adjacent the ventilating slots 42' and overlie a portion of said slots and cooperate with the diverging deflecting plates 43 in preventing a direct draft downwardly through the cap into the chimney or globe 13 but 110 which will permit a free passage of air upwardly through the chimney and outwardly of the cap.

Having thus described my invention what I claim is:—

120 A lantern having a burner, a globe therefor, a plate provided with an inclined wall to rest on the upper end of said globe and having openings therethrough, deflecting elements secured to said wall and disposed 125 over and partly closing said openings, a cap over said plate, an expansive spring intermediate said cap and plate, said cap be-

ing closed at its top and having draft openings through its side walls, deflectors integral with and struck out from said plate to provide the first mentioned openings, said 5 deflectors extending over and above said deflecting elements, and resilient fastening members extending from said cap through said plate intermediate the first mentioned openings and being deflected in opposite di-

rections and in contact with the lower surface of said plate.

In testimony whereof I affix my signature in presence of two witnesses.

EDWARD D. GRIFFITH.
